DESIGN FOR A LABORATORY WORKBENCH

Johan Bjorksten, Chicago, Ill.

Application September 4, 1945, Serial No. 121,836

Term of patent 14 years

(Cl. D33—7)

To all whom it may concern:

Be it known that I, Johan Bjorksten, a citizen of the United States, residing at 5534 S. Cornell Avenue, Chicago, in the county of Cook and State of Illinois, have invented a new, original, and ornamental Design for Laboratory Workbench, of which the following is a specification, reference being had to the accompanying drawings, forming part thereof.

Figure 1 is a top perspective view of a labora-

tory workbench showing my new design;

Figure 2 is an end elevational view;

Figure 3 is a side elevational view; and

Figure 4 is a top plan view thereof.

The other side of the hood is substantially the same as that shown.

I claim:

The ornamental design for a laboratory workbench, substantially as shown, and described.

JOHAN BJORKSTEN.
